UNITED STATES PATENT OFFICE.

JOSEPH DEVLIN SMITH, OF MARSHALLTOWN, IOWA.

DOOR-OPERATING MEANS.

1,401,202.

Specification of Letters Patent. Patented Dec. 27, 1921.

Application filed March 21, 1921. Serial No. 454,154.

To all whom it may concern:

Be it known that I, JOSEPH DEVLIN SMITH, a citizen of the United States of America, and resident of Marshalltown, Marshall county, Iowa, have invented a new and useful Door-Operating Means, of which the following is a specification.

The object of this invention is to provide an improved mechanism adapted for manual operation to open and close swinging doors from a position removed considerably from the doors, as for instance from a location within a vehicle standing in front of the doors.

15 A further object of this invention is to provide in such a mechanism an arrangement for automatically latching the doors in either open or closed position.

20 A further object of this invention is to provide a door-operating means the mechanism of which is arranged in large part within the building on which the doors are mounted.

25 A further object of this invention is to facilitate the movement of the doors by arranging that one of the pair shall start its opening and closing movement considerably in advance of the other, whereby the momentum of the moving door is applied to 30 initiate the movement of the other.

With these and other objects in view, my invention consists in the construction, arrangement and combination of elements hereinafter set forth, pointed out in my 35 claims and illustrated by the accompanying drawing, in which—

Figure 1 is a perspective view of a building having its doors equipped with my improved mechanism. Fig. 2 is an interior 40 elevation showing a part of the wall and doors and that portion of the mechanism located within a building. Fig. 3 is a plan of the mechanism, partly in section on the line 3—3 of Fig. 2. In Figs. 1, 2 and 3 the 45 mechanism is shown in the closed position of the doors. Fig. 4 is a detail perspective view, on an enlarged scale, showing the latching means in the position for latching the doors open.

50 In the construction of the device and its mounting as shown the numeral 10 designates the wall of a building formed with a doorway in which double doors 12, 13 are hinged at their outer margins in a common 55 manner. A supporting frame 14, which may well be formed of a metal bar of yoke-

shape, is mounted in a horizontal position above the doorway and secured to the wall 10, said frame being located just above said doorway and the position normally occupied 60 by the door 12 when in closed position. The yoke-shaped frame 14 has its closed end spaced a suitable distance from the wall 10 and substantially parallel therewith, and a rock shaft 15 is arranged substantially at 65 right angles to said walls and is journaled for rotary oscillation in the closed end of said yoke frame and in the wall above the doorway. The rock shaft 15 has its outer end extending a suitable distance away from 70 the wall, and an operating member 16 is pivoted to said outer end by a bolt or pin 16' arranged horizontally and parallel with said wall, the upper end of said operating member preferably being forked to receive a flat- 75 tened end portion of the rock shaft.

Brackets 17, 18 are mounted on the inner face of the wall 10 directly above the doorway therein, and each of said brackets is in the vertical plane of the hinges of one of the 80 doors 11 or 12. A short shaft 19 is journaled in the bracket 17 and fixed to said shaft is a pinion 20. A short shaft 21 is journaled in a vertical position in the bracket 18, and fixed to said shaft is an arm 85 or crank 22 extending away from the wall. Fixed to the lower ends of the short shafts 19 and 21, or suitably formed thereon, are bent levers 23, 24 respectively, each of said levers having a short arm secured at one end 90 to the respective shaft and extending away from the wall and inwardly of the building when the doors are closed as shown, and a long arm extending inwardly on an oblique line toward the free margin of the adjacent 95 door. The long arms of the bent levers 23, 24 are pivotally connected by links 25, 26 respectively to the free marginal portions of the doors 11, 12, near the upper ends thereof.

A rack bar 27 is horizontally arranged 100 and adapted for sliding movement in bearings 28 carried by the inner face of the wall 10 above the doorway, and the toothed portion of said rack bar is in mesh with the pinion 20. A pitman 29 is arranged in 105 horizontal position adjacent the wall 10 and in a portion of its length is parallel with said wall. The pitman 29 has one end portion formed as a collar or bearing 30 engag- 110 ing and adapted for limited sliding move- ment on the smooth portion of the rack bar 27. The pitman 29 is offset intermediate of

its ends away from the wall 10 and has its opposite end pivotally connected to the arm or crank 22 of the rock shaft 21. A link 31 is pivotally connected at one end to and between the ends of the pitman 29, extends in a plane substantially parallel with the wall 10, and is pivotally connected at its opposite end to a downwardly extending crank 32 formed on the inner end of the rock shaft 10 15. Spaced set collars 33, 34 are mounted on the smooth portion of the rack bar 27, on opposite sides of the collar or bearing portion 30 of the pitman 29, and both of said set collars are spaced from said collar 15 or bearing portion when the doors are in closed position.

A latching plate 35 is fixed to the outer face of the wall 10 beneath the rock shaft 15. A latching rod 36 is arranged parallel 20 with and beneath the rock shaft 15 within the yoke frame 14, and the inner end of said rod is adapted to engage selectively in either of a plurality of holes 37 formed in the latching plate 35. In this instance the 25 holes 37 are two in number and are so arranged that when the latching rod engages therein the doors 11, 12 are latched in fully closed or in open position substantially at right angles to the wall 10. The latching 30 rod 36 is adapted for limited sliding movement in spaced brackets 38, 39 fixed rigidly to and depending from the rock shaft 15, and an expansive coil spring 40 is coiled on said rod, impinges at one end the rearmost 35 bracket, 38, and at its forward end a collar 41 or similar member fixed to said rod. The outer end of the latching rod 36 is pivotally connected, as by links 42, to the operating member 16 at a point spaced materially below the pivot 16' thereof. The 40 spring 40 acts to press the rod into latching engagement with the plate 35, when the inner end of said rod is in such position as to enter either of the holes 37 therein.

In practical use, the doors 11, 12 being closed and latched by engagement of the rod 36 with the right hand hole 37, the operator grasps the operating member 16 and first pulls outwardly thereon to apply draft to 45 the rod 36 through the links 42 and cause said rod to leave the position of engagement with the latching plate 35, thus compressing the spring 40. Holding the latching rod out of engagement by continued force applied outwardly to the lower end of the operating member, the operator next swings the lower end of said operating member to his left, as he faces the building, thus rocking the shaft 15 clockwise. This movement 50 causes the latching rod to be moved through an arc on the axis of the rock shaft, its inner end sliding across the face of the plate 35 toward the other hole 37, which also are arranged in an arc concentric with said rock 55 shaft. Rocking movement of the shaft 15

as described exerts a pull on the link 31, through the crank arm 32, thus reciprocating the pitman 29 to the left of the operator (to the right, Figs. 2 and 3), which in turn results in an oscillation of the crank arm 70 22 and short shaft 21 and a movement of the bent lever 24 through an arc in the general direction indicated by the arrow *a* in Fig. 3. Such movement causes a pushing force to be applied to the free marginal portion of the door 12 through the link 26, thus tending to swing said door open on its hinges. As this action is taking place, and after the door 12 has opened substantially 75 half way and has gained considerable momentum in its movement, the collar portion 30 of the pitman, which to this point has been sliding freely on the rack bar 27, engages the set collar 34 and initiates a sliding movement of said rack bar toward the 80 hinged margin of the door 11. Such movement of the rack bar 27 causes an oscillation of the pinion 20, thus causing a movement through an arc of the bent lever 23 in the general direction of the arrow *b* in 85 Fig. 3; which movement in turn causes a pushing force to be applied to the inner marginal portion of the door 11, through the link 25, thus tending to swing said door open on its hinges. The opening movement 90 of the door 11 does not begin until the door 12 is well open, but both doors reach open (or closed) position at the same time, as the radius of the pinion 20 is correspondingly less than that of the crank arm 22, so that 100 the swinging movement of the door 11 is more rapid than that of the door 12.

When the doors 11, 12 have reached the desired point in their opening movement the inner end of the latching rod reaches 105 the other hole 37 and is forced therein by the spring 40, thus latching the doors in open position.

When it is desired to close the doors the operating member is pulled outwardly at 110 its lower end to release the latching rod 36 and then moved laterally in the opposite direction to that previously described, thus rocking the shaft 15 reversely and causing a pulling force to be applied to the link 31 through the crank arm 32. This moves the pitman 29 to the left (Fig. 3) and oscillates the crank arm 22 and shaft 21 opposite to the arrow *a*, thus pulling on the bent lever 24 and tending to close the door 12. In the first part of the last named movement of the pitman 29 the collar 30 thereof slides freely on the rack bar 27, until it reaches the set collar 33, after which it 115 causes reciprocation of said rack bar to the left, oscillation of the pinion 20 and shaft 19 and a pulling movement on the bent lever 23 to the end of closing the door 11. For the reason above stated, the door 11 reaches 120 closed position at the same time as the door 130

12 and thereupon the latching rod reaches the first hole 37 and is caused to enter same by action of the spring 40, thus latching the doors in closed position.

5 By starting the movement of one door at a time, in either direction, less force is required to initiate the movement, and when such door is well under way its momentum is applied to start the other door, thus 10 greatly facilitating the operation.

I claim as my invention—

1. Door operating means, comprising a rock shaft, shafts arranged in vertical position adjacent hinged margins of the doors, 15 bent levers fixed to said shafts, pivotal connections between said levers and the free marginal portions of the doors, a pinion on one of said shafts, a crank arm on the other of said shafts, a rack bar slidably mounted 20 and having a toothed portion in mesh with said pinion, a pitman pivoted at one end to said crank arm and operatively connected at its opposite end to said rack bar, said rock shaft being formed with a crank 25 arm pivotally connected to and adapted to reciprocate said pitman.

2. Door operating means, comprising a rock shaft, shafts arranged in vertical position adjacent hinged margins of the doors, 30 bent levers fixed to said shafts, pivotal connections between said levers and the free marginal portions of the doors, a pinion on one of said shafts, a crank arm on the other of said shafts, a rack bar slidably mounted 35 and having a toothed portion in mesh with said pinion, a pitman pivoted at one end to said crank arm and having a sliding operative connection to said rack bar, said rock shaft being formed with a crank arm pivot- 40 ally connected to and adapted to reciprocate said pitman.

3. Door operating means, comprising a rock shaft, shafts arranged in vertical position adjacent hinged margins of the doors, 45 bent levers fixed to said shafts, pivotal connections between said levers and the free marginal portions of the doors, a pinion on one of said shafts, a crank arm on the other of said shafts having a substantially greater 50 radius than said pinion, a rack bar slidably mounted and having a toothed portion in mesh with said pinion, a pitman pivoted at one end to said crank arm and having a sliding operative connection to said rack 55 bar, said rock shaft being formed with a crank arm pivotally connected to and adapted to reciprocate said pitman.

4. Door operating means, comprising a rock shaft, shafts arranged in vertical position adjacent hinged margins of the doors, 60 bent levers fixed to said shafts, pivotal connections between said levers and free marginal portions of the doors, a pinion on one of said shafts, a crank arm on the other of 65 said shafts, a rack bar slidably mounted

and having a toothed portion in mesh with said pinion, a pitman pivoted to said crank arm and having operative connections to said rack bar, said rock shaft being formed with a crank arm pivotally connected to and adapted to reciprocate said pitman, and spring-pressed means for latching said rock shaft against oscillation.

5. Door operating means comprising the combination with a wall and a pair of doors 75 hinged at their outer margins thereto, of a support carried by said wall above said doors, a rock shaft journaled in said support and extending through said wall, shafts 80 vertically arranged within said wall adjacent the hinged margins of said doors, bent levers fixed to said shafts and having pivotal connections to the free marginal portions of said doors, a pinion fixed to one of said shafts, a crank arm fixed to the other 85 of said shafts, a rack bar slidably carried by the inner face of said wall and having a toothed portion in mesh with said pinion, a pitman pivoted to said crank arm and operatively connected to said rack bar, said rock 90 shaft being formed with a crank arm at its inner end, and a link pivotally connecting said pitman to the crank arm of said rock shaft.

6. Door operating means comprising the 95 combination with a pair of doors hinged at their outer margins, of a rock shaft journaled for oscillation, shafts vertically arranged adjacent the hinged margins of said doors, bent levers fixed to said shafts and 100 pivotally connected to the free marginal portions of said doors, a pinion fixed to one of said shafts, a crank arm fixed to the other of said shafts, a rack bar slidably mounted and having a toothed portion in mesh with 105 said pinion, spaced set collars on said rack bar, a pitman pivoted to said crank arm and having a collar portion slidably engaging said rack bar between and adapted to contact selectively with the set collars thereon, 110 said rock shaft being formed with a crank arm, and a link pivotally connecting said pitman to the crank arm of said rock shaft.

7. Door operating means comprising the 115 combination with a wall and a pair of doors hinged at their outer margins thereto, of a rock shaft suitably journaled and extending through said wall, shafts vertically arranged within said wall adjacent the hinged margins of said doors, connections between said 120 shafts and the free marginal portions of said doors for swinging the latter on their hinges, a pitman mounted for reciprocation within said wall, connections between said rock shaft and the pitman for reciprocating the latter, connections between said pitman and the vertical shafts for oscillating the latter, an operating member pivoted to the outer end of and depending from said rock shaft, a latching rod connected with said 125 130

rock shaft and also connected with said operating member, and means carried by said wall for engagement by said latching rod to hold said rock shaft against oscillation.

5 8. Door operating means comprising the combination with a pair of doors hinged at their outer margins, of a rock shaft, shafts vertically arranged adjacent the hinged margins of said doors, connections between 10 said shafts and the free marginal portions of the doors for swinging the latter on their hinges, a pitman mounted for reciprocation, connections between said rock shaft and the pitman for reciprocating the latter, connections between said pitman and the vertical 15 shafts for oscillating the latter, an operat-

ing member pivoted to and depending from the outer end of said rock shaft, a latching rod carried by said rock shaft and adapted for reciprocation and being spring-pressed 20 in one direction, said operating member also having pivotal connections to said latching rod to withdraw it against the action of said spring, and a latching plate formed with spaced means for engagement by said latching rod under the influence of said spring.

Signed at Marshalltown, in the county of Marshall and State of Iowa, this 24 day of February, 1921.

JOSEPH DEVLIN SMITH.
